FIG. 12.

FIG. 1 is a front elevational view of a garment hanger showing my new design;

FIG. 2 is a top plan view thereof;

FIG. 3 is a side-elevational view thereof;

FIG. 4 is a cross-sectional view taken along plane IV-IV of FIG. 1;

FIG. 5 is a cross-sectional view taken along plane V-V of FIG. 1;

FIG. 6 is cross-sectional view taken along plane VI-VI of FIG. 1;

FIG. 7 is a front elevational view of a modified form of the garment hanger shown in FIG. 1;

FIG. 8 is a top plan view of FIG. 7;

FIG. 9 is a side-elevational view of FIG. 7;

FIG. 10 is a cross-sectional view taken along plane X-X of FIG. 7;

FIG. 11 is a cross-sectional view taken along plane XI-XI of FIG. 7; and

FIG. 12 is a cross-sectional view taken along plane XII-XII of FIG. 7.

The characteristic features of this design reside in the downwardly increasing cross-sectional measurements of

the header section as indicated in FIGS. 4 through 6 and 10 through 12.

This application is a continuation-in-part of design application Ser. No. D.10,140, filed Jan. 12, 1968, now abandoned.

I claim:

The ornamental design for a garment hanger, substantially as shown and described.
